UNITED STATES PATENT OFFICE.

WILLIAM H. DE FORD, OF DES MOINES, IOWA, ASSIGNOR TO E. DE TREY & SONS, OF PHILADELPHIA, PENNSYLVANIA, A PARTNERSHIP.

MOUTH-INHALER.

1,050,620.

Specification of Letters Patent. Patented Jan. 14, 1913.

Application filed February 20, 1912. Serial No. 678,885.

To all whom it may concern:

Be it known that I, WILLIAM H. DE FORD, a citizen of the United States, residing in Des Moines, Iowa, have invented certain 5 Improvements in Mouth-Inhalers, of which the following is a specification.

One object of my invention is to provide a structure particularly adapted for use in administering anesthetics through the 10 mouth, and more particularly has to do with a novel form of inhaler especially adapted to fit the mouth of a patient so as to permit of the passage of a gaseous anesthetic.

Another object of the invention is to provide 15 an inhaler especially adapted for the administration of anesthetics through the mouth; the arrangement of parts being such as to permit of free access to the nose, and eyes, in order that these organs or their associated parts may be operated on, and at 20 the same time provide a firm rest or support for the hand of the operator.

These objects and other advantageous 25 ends I secure, as hereinafter set forth, reference being had to the accompanying drawings, in which:—

Figure 1 is a side elevation of my inhaler showing it as employed for the administration of an anesthetic by the mouth; 30 Fig. 2 is a front elevation of the inhaler; and Fig. 3 is a vertical, longitudinal section taken on the line a—a, Fig. 2.

In the above drawings the inhaler is illustrated as consisting of a single integral 35 metal or other structure 1 having a tubular mouth-piece 2, designed to enter the mouth of the patient; its interior being in connection with a tubular portion at the opposite end of the inhaler through a relatively 40 flat passage 4 in the body of the inhaler structure. The tubular end 3 is designed for connection to any of the well known forms of conduits through which a gaseous anesthetic may be delivered and it will be 45 noted that the side portions of the upper part of the inhaler structure are flared, as indicated at 5, to form a mouth cover. These side extensions project above the tubular mouthpiece 2 and are united to form a por-

tion 6 designed to fit over the upper lip of 50 a patient. In addition the inhaler structure is provided with a projecting rib 7, designed to connect the lower portions of said members 5 and to fit closely against the lower portion of the lower lip of a patient; 55 the construction and shape of the parts being such as to provide a tube fitting the upper lip, from which it extends downwardly over the corners of the mouth and across the lower portion of the lower lip. 60

It is to be noted that the outer part of the inhaler opposite the tube 2 is relatively flat and with the part 6 is so formed as not to interfere with the free access to the nostrils. 65

Under operating conditions the inhaler is held in place by a strap 8 which engages suitable projections 9 and rests upon the face of a patient in the position shown in Fig. 1 (it being understood that the head is 70 supported in the proper position) under which conditions an anesthetic may be delivered to the patient through the passages 3, 4, and 2; the flat outer surface of the inhaler providing convenient rest for the hand 75 of a surgeon operating on the nose.

If desired an inflatable rubber rim 10 may be mounted in any suitable manner upon the edges or face portion of the inhaler for the purpose of preventing leakage 80 of air and to provide a cushion between the face of the patient and the inhaler.

I claim:

1. The combination in an inhaler of an integral structure consisting of a concave 85 body formed to fit the face of a patient, and provided with a peripheral flange; a mouth tube projecting from substantially the center of said concave body; and a supply pipe integral with the mouth tube extending 90 substantially at right angles to the latter and formed to fit the chin of a patient.

2. The combination in an inhaler of an integral structure consisting of a concave 95 body formed to fit the face of a patient, and provided with a peripheral flange; an integral mouth tube projecting from substantially the center of said concave body;

and a supply pipe integral with the mouth piece; said supply pipe projecting substantially at right angles to the general line of the mouth tube and being indented beyond said peripheral flange so as to fit the patient's chin.

In testimony whereof, I have signed my

name to this specification, in the presence of two subscribing witnesses.

WILLIAM H. DE FORD.

Witnesses:

EDGAR T. FEE,
EDWIN PROCTOR.
